UNITED STATES PATENT OFFICE.

FRED MASON MARTIN, OF NEW YORK, N. Y., ASSIGNOR TO AMERICAN SMELTING AND REFINING COMPANY, OF NEW YORK, N. Y., A CORPORATION OF NEW JERSEY.

ORE-STREAM HOPPER.

Original application filed October 28, 1919, Serial No. 333,892. Divided and this application filed September 11, 1920, Serial No. 409,587. Renewed December 12, 1922.

To all whom it may concern:

Be it known that I, FRED MASON MARTIN, a citizen of the United States, and resident of New York city, in the county of Kings and State of New York, have invented certain new and useful Improvements in Ore-Stream Hoppers, of which the following is a specification.

The invention relates to a machine for receiving a mass of material which cannot be readily handled such as wet concentrates, ores, slimes, clays and similar plastic material and for converting the mass into a disintegrated stream having a regulated flow per unit of time. This application constitutes a division of my copending application on apparatus and method for sampling ore, Serial No. 287,137, filed April 3, 1919, and also constitutes a division of application, Serial No. 333,892, filed October 28, 1919.

In the parent application there was disclosed a method which included the steps of first forming a constant and uniform flow of material in a compact, solid stream. This compact stream was then acted upon by a disintegrator so as to form an open stream with the particles relatively small and spaced apart. By means of a rotary sampler there was a periodic abstraction of small uniform samples from this open stream which samples were assembled in one mass so as to obtain a fair sample of the entire original mass.

This application features the stream handling elements of the original disclosure in distinction from the combination which includes the sampling mechanism and in distinction from the combination which includes the disintegrating mechanism.

The primary object of the invention herein featured is to provide a simple form of apparatus which will receive the difficultly handable material in bulk and which will feed the same therefrom in a constant stream of uniform cross section thereby to insure the feeding of equal amounts in succeeding units of time.

Still another object of the invention herein disclosed is to provide a stream forming device of rugged construction to withstand the hard working conditions to which heavy ore handling machines are usually subjected and at the same time to provide a machine

which can be operated economically and independently of the character of material handled.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

Figure 1 is an enlarged view of the material receiving hopper element of a machine constituting a preferred embodiment of my complete invention and with parts of the hopper broken away to show internal construction;

Figure 2 is an enlarged view in right end elevation of the device shown in Figure 1 and with parts broken away;

Figure 3 is an enlarged plan view of the hopper looking down upon the device shown in Figures 1 and 2; and

Figure 4 is a vertical sectional view taken on the line 4—4 of Figure 1.

In the drawings, there is shown a suitable supporting framework upon which is mounted a fixed open-top hopper 16 adapted to receive the material to be treated. The material in the hopper is moved by a belt conveyor 17 defining the bottom of the hopper across the hopper thereof, is discharged therefrom and is permitted to fall freely into engagement with a disintegrating device 18 which acts on the material to break up the stream discharged from the hopper. The broken-up stream is then permitted to fall onto a sampler or other treating device 95 more particularly defined in the parent application above identified.

It will be noted that the receiving end of the hopper is provided with a pair of oppositely disposed, downwardly and inwardly inclined deflectors 23 which act to distribute the material discharged into the same and to dispose the same evenly on opposite sides of the longitudinal medial line through the hopper. Each of the deflectors is pivotally connected to the adjacent side of the hopper at its upper edge. The deflectors are each held in adjusted swinging position by

means of a lifting rod 24 which passes through the adjacent side and is held in set position by nuts 25 as shown in Figure 2. The hopper is provided at its discharge end 5 with an opening 26 having a width equal to that of the hopper but relatively small in its vertical dimension as shown in Figure 2. A plow 27, triangular-shaped in plan as shown in Figure 3, is mounted at the discharge end of the hopper and is positioned above the opening 26. The plow is mounted for vertical adjustment on transverse bars 28 constituting internal braces for the hopper. Vertically adjustable hanging rods 29 10 connect the bars 28 with the advance edge and with opposite sides of the plow. By this construction the bottom edge of the plow is set at any desired distance above the conveyor 17 so as to regulate the depth of the stream of material delivered through 15 the opening 26 to the disintegrator 18.

The belt conveyor 17 includes an endless material-receiving belt 30, the upper run of which fits relatively close to the open bottom of the hopper as shown in Figure 25 4 and constitutes a movable bottom for said hopper. This belt is relatively wide and extends beyond opposite lateral sides of the hopper so as to minimize any tendency 30 of leakage between the hopper and the conveyor. The belt encircles an endless driving frame 31, and has its upper run resting on the frame and held thereto frictionally but is otherwise unsecured to the frame. A 35 plurality of longitudinally extending tracks, in Figure 4 shown to be four in number, extend parallel to the length of the hopper with the two inside tracks 32 positioned below the hopper and the two outside tracks 40 33 offset laterally to the outside of the hopper. The frame includes a series of transversely disposed bars 34 connected at their outer ends by roller chains 35. The frame is designed to engage and slide on the 45 tracks through roller casters 36. The chains of the frame are passed about end sprocket wheels, one set of which, 37, at the discharging end of the conveyor constitute driving sprockets and are mounted upon and driven 50 from a power shaft 38. The other set of sprockets 39 is carried by a shaft 40 mounted in take-up bearings 41 by means of which the tension on the conveyor frame is adjusted. The parts are so proportioned 55 and so spaced from the tracks that when the frame is carried from its horizontal path into its path around the sprocket wheels, the belt 30 is moved clear of the sprocket wheels thus permitting the use of a belt of 60 unusual width.

In operation, and assuming that several movable elements of the device are operatively connected to the power system so as to cause them to operate at the desired relative speed and assuming that load after load

of the material is dumped into the hopper, the device can be left by itself and will operate automatically.

The deflectors on opposite sides of the hopper tend to distribute the incoming loads 70 of material on opposite sides of the medial line through the nose of the plow and as the material is carried by the belt conveyor into engagement with the plow it will be caused to spread out in a layer of uniform 75 thickness and the conveyor will discharge the same uniformly through the outlet opening 26. As the layer of material is fed to the disintegrator, it is cut into longitudinal strips by means of the cutting disks, and the disintegrating wires moving upwardly 80 through the mass, usually at relatively high speed, will tend to break up the strips before the material is permitted to fall towards the sampler. Even if wet and sticky 85 the material is separated and falls in a stream of separate particles.

By means of a device of the character thus outlined it is possible to obtain a fair sample of the material, even though this 90 material be of a plastic nature and otherwise difficult to handle. With reference to the hopper an advantage is attained over any attempt to feed the irregular mass of material through an opening, the adjacent 95 sides of which are disposed in planes perpendicular to the direction of motion of the material, in that there is less stress upon the mechanism of the conveyor and less power consumed. 100

When the plow outlined is used the supply of material discharged by the conveyor to the disintegrator is more continual and uniform than heretofore for apparently the wet material does not exhibit any tendency to 105 pile up on the plow. Using a relatively large belt on the conveyor gives the feeder a large capacity at slow speed. Further, with the particular type of conveyor disclosed lateral or side creep of the belt is minimized 110 and belt tension is eliminated as the driving or carrying effect is proportioned to the weight of the load only and relative movement between the belt and its carrying frame is minimized so as to eliminate wear 115 on the underside of the belt.

Having thus described my invention, I claim:

1. In a device of the class described, the combination of a hopper provided with a discharge opening at one end, a conveyor constituting the bottom of the hopper, and adapted to move the contents of the hopper through said opening and a plow comprising a pair of substantially flat members positioned in intersecting vertical planes within said hopper, the vertical edges of each of said members facing the outgoing contents being in mutual contact to form a ridge for distributing the ma- 125 130

terial on each side of the medial line of movement of the material past the plow.

2. In a device of the class described, the combination of a hopper provided with 5 a discharge opening at one end, a conveyor constituting the bottom of the hopper, and adapted to move the contents of the hopper through said opening, a plow comprising a pair of substantially flat members positioned 10 in intersecting vertical planes within said hopper, the vertical edges of each of said members facing the outgoing contents being in mutual contact to form a ridge for distributing the material on each 15 side of the medial line of movement of the material past the plow and a single means for adjusting the position of the said members vertically to regulate the depth of the material discharged through the opening.

3. In a device of the class described, the combination of a hopper provided with a discharge opening at one end, a conveyor constituting the bottom of the hopper, and adapted to move the contents of the hopper 20 through said opening, a plow mounted in said hopper adjacent the discharge end of the conveyor and means in advance of the plow for distributing the material on each side of the medial line of movement of the 25 material past the plow.

4. In a device of the class described, the combination of a receptacle having a discharge opening at one end, a belt conveyor constituting the bottom of the receptacle 30 and adapted to feed the contents of the receptacle through said opening, a pair of downwardly and inwardly inclined deflectors positioned in said receptacle at the receiving end of the belt conveyor to distribute the material on opposite sides of the longitudinal medial line of the conveyor, 35 means within the receptacle in rear of the deflectors and in advance of the opening to level the material centered by the deflectors before it is passed by the conveyor 40 through the opening, means for varying the angle of inclination of the deflectors and means for varying the position of the plow 45 relative to the deflectors thereby to vary the character of the stream of material discharged from the hopper.

5. In a device of the class described, the combination of a receptacle having a discharge opening at one end, a belt conveyor constituting the bottom of the receptacle 45 and adapted to feed the contents of the receptacle through said opening, a pair of downwardly and inwardly inclined deflectors positioned in said receptacle at the receiving end of the belt conveyor to distribute 50 the material on opposite sides of the longitudinal medial lines of the conveyor, and means within the receptacle in rear of the deflectors and in advance of the opening to level the material centered by the 55 deflectors before it is passed by the conveyor through the opening.

6. In a device of the class described, the combination of a receptacle having a discharge opening at one end, a belt conveyor 60 constituting the bottom of the receptacle and adapted to feed the contents of the receptacle through said opening, a pair of downwardly and inwardly inclined deflectors positioned in said receptacle at the receiving end of the belt conveyor to distribute 65 the material on opposite sides of the longitudinal medial line of the conveyor, means within the receptacle in rear of the deflectors and in advance of the opening to 70 level the material centered by the deflectors before it is passed by the conveyor through the opening, means for varying the angle of inclination of the deflectors and means for varying the position of the plow 75 relative to the deflectors thereby to vary the character of the stream of material discharged from the hopper.

Signed at New York in the county of New York and State of New York this 3rd 80 day of Sept., 1920, A. D.

FRED MASON MARTIN.
